ATTORNEY.

UNITED STATES PATENT OFFICE

2,457,072

BURGLAR ALARM

Bernard W. Smith, Hartford, Conn.

Application October 25, 1946, Serial No. 705,746

5 Claims. (Cl. 116—90)

1

This invention relates to burglar alarms for windows and more particularly to devices such as are intended to operate an alarm upon unauthorized attempts to either open or close a window.

An object of this invention is to provide such an alarm which is particularly adapted for use in windows of buildings and which may be operated through the movement of the window sash.

A further object of the invention is to provide a burglar alarm which may be fitted in a conventional window frame in place of the ordinary sash pulley, so as to support the window sash by means of the conventional cord thereof, and which is operated by said cord for rendering an alarm.

Further objects and advantages of this invention will be more clearly understood from the following description and from the accompanying drawings, in which—

Fig. 1 is a sectional side view of my improved burglar alarm, on line 1—1 of Fig. 2, and showing a portion of the window frame and sash.

Fig. 2 is an elevational front view of said alarm with the front plate thereof removed.

As shown in the drawings, the numeral 5 denotes a portion of a conventional window frame in which there is ordinarily employed a sash 6 which moves in said frame for opening and closing the window.

In the embodiment of my invention shown, the alarm mechanism consists of a casing 7 having flanges 8 by means of which the said casing is positioned within an opening in the side of the window frame and secured therein by means of screws 9 which also secure in position a cover plate 10.

A pulley 11 is mounted upon a shaft 12 which is pivoted to said casing and rotates with the pulley. A gear 13 is also secured to said shaft and driven thereby to rotate a pinion 14 on the shaft 15 which carries an escapement or cam wheel 16. An actuating rocker lever 17 is secured to a shaft 18 which is also pivoted in the case and carries a hammer 10 and pull lever 20 that is actuated by a pull rod 21. A bell 22 is secured within the case 7 in position to be struck by the hammer 19.

As illustrated in Fig. 1, the sash 6 is hung by means of the cord 23 which is mounted over the pulley 11 and has a counterweight 24 secured to the end thereof for counterbalancing the sash 6.

In the operation of my improved burglar alarm, any movement of the window sash 6 by an unauthorized person to either raise or lower it will, through the cord 23, rotate the pulley 11 which

2

in turn will rotate the shaft 12, the gear 13 and the pinion 14, and thereby cause rotation of the cam wheel 16 to actuate the lever 17 against the action of the spring 17—a and vibrate the hammer 19 against the bell 22 to render an audible alarm signal.

When it is desired to make the mechanism of the said burglar alarm inoperative, the cord 21 may be pulled downwardly and secured in any desired manner, not shown, to retain the lever 17 out of engagement with the cam wheel 16, so that rotation of said wheel, during normal raising or lowering of the window sash, will not cause ringing of the bell 22.

15 It will be noted that my improved burglar alarm device, when conditioned to be operative, will operate immediately upon an attempt being made to move the sash 6 from a fixed position, and that movement of the sash in either direction will immediately cause the said device to render an alarm. Therefore, no setting of the device, or of the window sash, is required in order to make the said device operative other than to merely release the cord 21.

25 I claim:

1. A burglar alarm for a window having a frame, a sash slidable in said frame, a cord running along the side of said frame and having an end secured to said sash; the said alarm comprising a casing secured to the side of and within said frame, a pulley rotatable in said casing and adapted to receive said cord, weighted means within the frame providing frictional engagement between said cord and pulley for rotation of said pulley upon movement of the sash, a cam wheel rotatable by said pulley, a bell, and a hammer operable upon rotation of said cam wheel for striking said bell to render an audible signal.

2. A burglar alarm for a window having a frame, a sash slidable in said frame, a cord having one end thereof secured to said sash and its other end secured to counterbalancing means for suspending said sash; the said alarm comprising a casing having a cover plate secured to the side of and within said frame, a pulley rotatably mounted in said casing adjacent to said plate and projecting slightly therethrough for receiving said cord for rotation of the pulley upon movement of the sash, a cam wheel rotatable by said pulley, a bell adjacent the surface of said side, and a hammer operable upon rotation of the cam wheel for striking said bell to render an audible signal.

3. A burglar alarm for a window having a frame and a sash slidable in said frame, a cord having

one end thereof secured to said sash, counterbalancing means secured to the other end of said cord; the said alarm comprising a casing mounted in an opening in one side of and within the said frame, the said casing being open at said side and having a detachable cover plate at said side of the frame for closing said casing, a pulley rotatable in said casing and extending slightly through an opening in said cover plate for receiving said cord for rotation of the pulley upon movement of the sash, a cam wheel rotatable by said pulley, a bell within said casing and positioned adjacent to said plate opposite openings therein, and a hammer operable upon rotation of said cam wheel for striking said bell to render an audible signal.

4. A burglar alarm for a window having a frame, a sash slidable in said frame, a cord for suspending said sash; the said alarm comprising a casing having inner, upper and lower walls and mounted within an opening in the side of said frame, ears extending from said casing, mechanism contained within said casing and including a bell, a striker, cam means, and a pulley rotatably mounted within said casing and projecting slightly from the side of said frame and adapted to rotate said cam means for operating said striker to strike said bell, a cover plate for closing said casing extending over said ears, means securing said cam plate and ears to the side of the frame for securing the casing to the frame and closing said casing, the said cover plate having a slot therein to permit said pulley to project therethrough into the said frame; a cord secured

to the sash and running along the side of the frame, over said pulley and downwardly therefrom between the said inner wall of the casing and the cover plate and through the bottom wall 5 of the casing at the opposite side of the said side of the frame, a weight secured to the lower end of the cord for counterbalancing said sash, a lever connected to the striker and projecting through the inner wall of the casing for rendering said 10 striker inoperative by said cam means, and a pull cord for operating said lever.

5. For a burglar alarm of the character described, a window construction comprising a frame, a sash, a pulley within said frame, means 15 operable upon rotation of said pulley for rendering an audible signal, a flexible member connected to said sash and extending over said pulley for causing rotation of the pulley upon movement of said sash, and sash counterbalancing 20 weighted means within said frame connected to said flexible member for retaining it in driving engagement with the pulley.
